(57) **CLAIM**

The ornamental design for a watch setting, as shown and described.

DESCRIPTION

FIG. 1 is a top view of the watch setting showing my new design, the remainder of the watch being shown in broken lines for environmental purposes only and not constituting a part of the claimed design. For example, the pattern of the hands, which are dynamic with respect to position, the digits, and the hand strap are illustrated for clarification only.

1 Claim, 1 Drawing Sheet

FIG.1
